UNITED STATES PATENT OFFICE.

JACOB RUBEL, OF NEW YORK, N. Y., ASSIGNEE TO STANDARD MAIL ORDER COMPANY, OF NEW YORK, N. Y., A CORPORATION OF NEW YORK.

CATAMENIAL APPLIANCE.

1,144,253.

Specification of Letters Patent. Patented June 22, 1915.

Application filed March 20, 1915. Serial No. 15,718.

To all whom it may concern:

Be it known that I, JACOB RUBEL, a citizen of the United States of America, and residing in the city, county, and State of New York, have invented a certain new and Improved Catamenial Appliance, of which the following is a specification.

My invention relates to catamenial appliances and particularly to a protective covering adapted to carry an absorbent napkin and to protect the clothing of the wearer from stains.

In the accompanying drawing, Figure 1 is a perspective view of an illustrative embodiment of my invention; and Fig. 2 is a side elevation of the same showing an absorbent napkin in position.

The appliance, as illustrated, comprises a supporting tape 5 adapted to extend around the waist above the thighs. The free ends of this tape are passed through buckles 6 and 7 carried by looped tabs 8 and 9 sewed down by cross strips 10 and 11 at the opposite upper corners and on the outer face of the triangular fabric shield 12 at the front of the appliance. At the lower corner of this shield and also on the outer face thereof a cross strip 13 secures the upper end of a looped tab 14 in which the safety pin 15 hangs horizontally. A fabric shield 16 stitched to the tape 5 at the back of the appliance carries on its inner face a looped tab 17 in which also hangs horizontally a safety pin 18. Between these two safety pins and by means thereof an absorbent napkin 19 of any type may be suspended from the tape. Beneath this napkin extends the protector 20 comprising a sheet of rubberized cloth or the like constricted at the front but widening toward the rear, at which point it is continued upward over the buttocks by a gauze or mesh section 21 secured at its upper edge to the tape 5. Reinforcing bands 22 extend from the rubberized sheet 20 to the tape 5 at suitable intervals to relieve the mesh from strain. The protector and gauze section are tailored to fit the thighs snugly without wrinkling. At the front of the protector, a short tab 23 carries a button fastener 24 which engages any one of the outwardly faced studs 25 riveted to a tape 26 which hangs down outside the shield 12.

The triangular shield 12 with the three points of attachment for the ends of the tape

5 and the front of the napkin 19 distributes 55 the strain of the tightly drawn tape and is easier on the wearer as well as being flatter and therefore less likely to wrinkle the clothing than the ordinary method of tying the ends of the tape into a knot. The location 60 of the safety pin 15 on the outer face of this shield protects the wearer against contact with the metal of the pin. The pin 18 must be carried upon the inner face of the shield 16 to be accessible, but this is no objection 65 since the end of the napkin 17 overlies it. The studs 25 on tape 26 permit the adjustment of the protector 20 to any desired degree of snugness beneath the napkin 19. The attachment of the tape 26 at the top of 70 the shield 12 affords room for the free end of the napkin held by the pin 15, while the shield and napkin end together protect the body from all the metal fasteners at the front of the device. Obviously the front end 75 of the shield and napkin may be readily temporarily detached and swung down out of the way to permit of the ordinary evacuations. There are no parts apt to be injured by boiling and the appliance may therefore 80 be readily sterilized. While the appliance may be made in various sizes, the tapes 5 and 26 afford means for a considerable take-up or let out to fit it to the wearer.

I claim as my invention:—

1. A catamenial appliance comprising a suspension tape, a protector permanently secured at the rear thereto, an independent triangular shield at the front of the appliance, means at the opposite upper corners of said shield for separately fastening the ends of said tape thereto, and means for securing at the lower corner of said shield the front end of an absorbent napkin, together with a tape secured to the upper portion of said shield 90 and overlying the outer face thereof, for engaging the front end of said protector.

2. A catamenial appliance comprising a suspension tape, a protector permanently secured at the rear thereto, an independent 100 shield arranged at the front thereof, means on the outer face of said shield for securing the ends of said tape separately thereto, means at the lower portion of said shield for detachably engaging the front end of an 105 absorbent napkin, a tape depending from the upper portion of said shield, overlying the outer face thereof and having adjustable

means for detachably engaging the front end of said protector, in combination with a shield at the back of said appliance, lying within the protector and having means for detachably engaging the rear end of said napkin.

In testimony whereof I have signed my

name to this specification, in the presence of two subscribing witnesses.

JACOB RUBEL.
